ARTICULATED LOCOMOTIVE TRUCK FRAME

James Nelson Green, Copper Cliff, Ontario,
Canada

Application March 15, 1945, Serial No. 582,821

6 Claims. (Cl. 105—175)

1

This invention relates to improvements in a locomotive and appertains particularly to the running gear therefor.

An object of the invention is to provide a locomotive or other railway unit whose trucks or running gear impose the minimum of resistance to movement when the unit is negotiating a section of curved track.

Another object of the invention is to provide a locomotive or like railway unit having an improved design of trucks and means for mounting and connecting the same in what might be called hinged or articulated relation whereby the same are allowed to swing freely to traverse an arc of relatively small radius.

Another object of the invention is to provide an articulated locomotive or other unit of railway rolling stock, where it is desired to connect or couple as by draw bars on the trucks per se, rather than on the locomotive body, whose own pair of trucks are so coupled that they may swing freely each on its central vertical pivot through a substantial angle without binding.

Another object of the invention is to provide a locomotive especially one of the electric or Diesel double ended type wherein the frame and truck structure are so connected and linked as to afford greater flexibility for negotiating curves and/or rough or uneven tracks, maintain proper distribution of weight and a low, direct line of transmission of draft without sacrificing stability.

Yet another object of the invention is to provide a locomotive pivotally mounted on each of a pair of trucks that are connected by an articulated coupling allowing free movements at the pivot connections with the respective units of the articulated vehicle and relative vertical hinging at the confronting ends of the trucks without disturbing the direct line of transmission of draft by means of a novel design for the ends of the trucks and a special linkage therebetween so that no looseness of the pivots or cross castings is required.

Another object of the invention is to provide an electric locomotive or the like supported on a pair of centrally pivoted, coupled trucks wherein the alignment of and distance between the respective pivots and inter-truck coupling remain constant.

Another object of the invention is to provide an articulated electric locomotive, whose running gear includes a pair of trucks coupled together and each centrally pivoted to the locomotive frame, wherein the coupling comprises a floating, spring-suspended linkage embodying an oscillating bearing for each truck.

2

A still further object is to provide a railway vehicle and especially an electric locomotive or the like with improved, direct line of draft running gear, that will allow of negotiating more acute curves without binding, impart greater stability, strength and safety and reduce maintenance costs whereby the same is rendered commercially desirable.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a side elevation of a double ended type of electric locomotive embodying this invention;

Figure 2 is a plan view of the articulated trucks or running gear thereof;

Figure 3 is a similar plan view illustrating the linked trucks negotiating a section of acutely curved track;

Figure 4 is an enlarged plan showing structural details of the adjoining ends of the articulated trucks;

Figure 5 is a side elevation of the articulating link;

Figure 6 is a vertical section thereof as taken on line 6—6 of Figure 4 with the left oscillating bearing shown in elevation; and

Figure 7 is an end elevation thereof.

In conventional electric locomotives of the two truck type, it is common practice to couple the trucks by a snug fitting pintle uniting the tongues on the confronting ends of the trucks and to allow the trucks to hinge, when the locomotive is taking a curve, a substantial degree of looseness is provided as between the male and female crown castings, where the trucks pivot to the locomotive frame. As the swinging of the trucks on a curve throws the tongue-connecting pintle out of line, substantially increasing the distance

between truck pivot centers by line passing through the tongue pintle, the truck centre pivots are drawn together until the slack or looseness there allowed is fully taken up or until the crown castings bind, that is the limit of curve the coupled trucks can negotiate. Then should an unevenness in the track cause one of the trucks to teeter,

the vertical as well as horizontal displacement of the tongue-connecting pintle out of line with the truck centre pivots may cause the truck to leave the track.

The present invention provides a coupling or connecting link between the companion, centrally pivoted trucks that remains constantly aligned horizontally with the pivots, floating vertically in spring damping suspension, and provided with horizontal oscillating bearings to allow either truck to rock or teeter as it passes over rough or uneven tracks.

Carrying out this invention I employ a pair of the usual trucks 1 and 2 each having the regular main frame 3 on the top of the centre cross bed 4 of which the female crown casting 5 is mounted midway of the sides of the frame; these each receive a true fitting male crown casting 6 affixed to the underside of the frame 7 of the locomotive body 8, which respective pairs of male and female crown castings constitute axial pivot connections between the locomotive body and trucks by which the latter are allowed to swing horizontally on a fixed vertical axis.

In a motor driven unit such as the two truck electric locomotive shown it is desirable to provide a draft coupling between the confronting or adjacent ends of the trucks 1 and 2 and the heretofore used truck-carried tongues prove inadequate for, as will be seen in Figure 3, the distance between the truck centres, or male and female crown castings 5 and 6, by way of a pair of pin-coupled tongues on the longitudinal median of the respective trucks has increased too greatly. Consequently I suspend a truck link or coupling 9 from a fixed point at the mid centre of the locomotive frame 7 which thus remains always a fixed distance from and midway between the crown casting pivot centres of the trucks and in constant alignment therewith.

For engagement by this link or coupling 9 the confronting or adjacent ends of the trucks 1 and 2 each have a supplementary or coupling frame piece 10 extending beyond and mounted on the end of the main truck frame 3. This supplementary coupling frame 10 has a transversely extending cross piece 11 spaced from the end of the truck frame 3 and formed as the arc of a circle described with the pivot axis of the crown castings 5 and 6 as centre. These arcuate coupling frame cross pieces 11 of the respective trucks preferably approach fairly near one another and obviously, since each is described from its truck pivot as centre, they remain a fixed distance apart as one or both of the trucks swings on its axis. In cross section the cross piece 11 is square.

The coupling 9 is composed of similar upper and lower complementary halves 9a and 9b separably connected by the nuts and bolts 12 and 13. Nesting in suitable confronting concavities 14 in the halves of the coupling 9 are housed a pair of horizontal, transversely disposed rotatable bearing sleeves 15, one on either side of the transverse median, which sleeves have each a longitudinally extending, square passage-way 16 and arced throughout its length to accommodate the coupling frame cross piece 11 that slides freely therethrough.

For anchoring the coupling 9 to the underside of the locomotive frame 7 to hold it against transverse displacement and yet allow of limited vertical movement to compensate for rocking of the trucks as they ride over rough and uneven sections of track; a laterally spaced pair of sup-

porting rods 17 depend from the locomotive frame 7 and pass loosely through vertical bores 18 in the coupling 9 between the spaced bearing sleeves 15 and on each rod 17 above and below the coupling 9 is a compressed coil spring 19, the whole being confined in assembly by the nuts 20 threaded on the lower ends of the said rods whereby the said coupling is floated in this movement-damping suspension.

As the locomotive 8 negotiates a curved section of track, the trucks 1 and 2 swing oppositely on their pivots at the crown castings 5 and 6 but their arcuate coupling frame cross pieces 11 are held in firmly linked draft coupling as they travel sideways without binding through the bearing sleeves 15 in the locomotive frame supported coupling 9 that remains equally spaced from and constantly aligned with the truck pivots. On either straight or curved track the trucks may rock freely, within the limits required, when the arcuate cross pieces 11 cause their respective rotatable bearing sleeves 15 to turn or oscillate in the coupling 9.

From the foregoing description taken in connection with the accompanying drawings, it will be manifest that an articulated, two truck, electric locomotive is provided that will fulfill all the necessary requirements of such a device, but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention what I claim as new and desire to secure by Letters Patent is:

1. In an articulated locomotive having a pair of trucks, each centrally pivoted to the locomotive frame, adjacent ends on said trucks each formed as an arc described from the respective truck pivot as a centre, and a vertically movable, connecting link suspended from the locomotive frame, spring damped in its vertical movements and with which said arcuate ends have relatively transverse sliding engagement.
2. In an articulated locomotive having a pair of trucks, each centrally pivoted to the locomotive frame, adjacent ends on said trucks each formed as an arc described from the pivot as a centre, a vertically separable, two piece connecting link suspended from the locomotive frame and having spaced transverse concavities in which said arcuate ends have relatively transverse sliding engagement and means for holding said link against transverse displacement.
3. In an articulated locomotive having a pair of trucks, each centrally pivoted to the locomotive frame, adjacent ends on said trucks each formed as an arc described from the pivot as a centre, a link suspended from the locomotive frame connecting the arced ends of said trucks normally aligned with the truck pivots, means for holding said link against lateral displacement, means for allowing limited vertical floating thereof and rotatable bearing sleeves therein through which said respective arced truck ends may freely slide.
4. A means of articulating the running gear of a locomotive having a pair of trucks each centrally pivoted to the locomotive frame consisting of an arcuate formation on the adjacent end

of each truck wherein the arc is described with the truck pivot as a centre, a link engaging said adjacent arcuate truck ends comprising a coupling block, a longitudinally spaced pair of rotatable bearings disposed transversely in said coupling block and through which said arcuate truck ends have relatively transverse sliding engagement and means suspended from said locomotive frame for holding said link in substantial alignment with said pivots.

5. A means of articulating the running gear of a locomotive having a pair of trucks each centrally pivoted to the locomotive frame consisting of an arcuate formation on the adjacent end of each truck wherein the arc is described with the truck pivot as a centre, a vertically movable link engaging said adjacent arcuate truck ends and with which they have relatively transverse sliding engagement, means suspended from the locomotive frame for holding said link against lateral displacement and resilient means mounted on said first mentioned means for damping any vertical displacement of said link.

6. An articulated locomotive comprising a pair of trucks, a female crown casting mounted centrally on the frame of each, a locomotive body surmounting said trucks having a frame on the underside of which a longitudinally spaced pair

of male crown castings are provided to engage in said truck-carried female crown castings to afford each truck a vertical pivot axis, a vertically floating coupling link suspended from the frame of said locomotive, a pair of longitudinally spaced, transversely disposed rotatable bearing sleeves in said link, and a coupling frame on the adjacent end of each of said trucks having a transversely extending bar in the form of an arc described from the truck pivot as a centre passing through the respective rotatable bearing sleeves in said link and slideable freely therein.

JAMES NELSON GREEN.
